SPRINKLER HEAD SHIELD

Paul Engel, Beaumont, Calif., assignor to A-E-G Mfg.
Co., Beaumont, Calif.

Filed Aug. 10, 1970, Ser. No. 24,404

Term of patent 14 years

U.S. Cl. D23—7   Int. Cl. D23—07

FIG. 1 is a perspective view of a sprinkler head shield embodying my new design;

FIG. 2 is a top plan view of the same;

FIG. 3 is a side elevation; and

FIG. 4 is a sectional view, taken at 4—4 in FIG. 2.
I claim:

The ornamental design for a sprinkler head shield, as shown.
